UNITED STATES PATENT OFFICE.

HENRY M. DAYTON AND NELLIE DAYTON, OF SEATTLE, WASHINGTON.

FINGER RING.

Application filed December 4, 1928. Serial No. 323,621.

This invention relates to finger rings and particularly to binary rings, that is, a ring composed of two joined rings.

The general object of our invention is to

5 provide an engagement and a wedding ring, the wedding ring being so constructed that it will fit against and may be joined to the engagement ring and be inseparable therefrom, thus symbolizing the inseparable joining of two persons by the wedding ceremony.

Ordinarily a wedding ring and engagement ring are separate rings and as a consequence of the fact that the engagement 15 ring usually supports a relatively large bezel and stone, the wedding ring is held on the finger separated from the engagement ring and there is a space seen between the rings and the two rings do not present a neat 20 appearance upon the finger. It has been proposed to modify the form of the engagement ring so that the wedding ring may be worn closely adjacent to or joined to the engagement ring but this requires that the 25 engagement ring shall be modified from its ordinary or usual form and the engagement ring at the bezel or at the junction of the crown setting and the body of the ring shall be extended outward so that the wedding 30 ring may fit beneath the projecting portion of the bezel or the jewel prongs.

Engagement rings to-day are of such designs as not to permit this undue projection of the jewel supporting portion of the engagement ring.

The object of the present invention is to provide for combining a wedding ring with an engagement ring and to modify the wedding ring so that it may be fitted against 40 and interfit with a modern form of engagement ring without in any way altering the engagement ring itself and specifically to cut away the wedding ring so as to form a recess which will receive the jewel supporting portion of the engagement ring or any lateral projection at this point, thus permitting the wedding ring to fit snugly against the engagement ring and permit it to be soldered or pinned thereto or engaged therewith by 45 screws.

Our invention is illustrated in the accompanying drawing, wherein:—

Figure 1 is a side view of a ring constructed in accordance with our invention;

55 Figure 2 is an edge elevation of a combined wedding ring and engagement ring;

Figure 3 is a section on the line 3—3 of Figure 1;

Figure 4 is a section on the line 4—4 of Figure 2.

Referring to the drawings, 10 designates the wedding ring and 11 the engagement ring. This may be of any suitable or usual form such as is commonly used today and it is shown as being widened at 12 to form 65 a support or crown setting for the jewel 13. Thus the jewel supporting portion of the engagement ring is relatively wide while the band 11 of the ring proper is relatively narrow.

The wedding ring 10 is of any usual or suitable design but in order that the wedding ring may lie flat against the side of the engagement ring, the wedding ring is cut away at 14 to an extent sufficient to receive the 75 crown setting 12 and fit closely thereto. If the engagement eventuates in a wedding, the wedding ring is slipped upon the bride's finger against the engagement ring and later the wedding ring is soldered, pinned or attached by screws to the engagement ring. We do not wish to be limited to any particular means for attaching the wedding ring to the engagement ring but we have illustrated in the sectional view in Figure 3 the wedding 80 ring as being attached to the engagement ring by means of pins or screws 15, the use of screws permitting the two rings to be readily detached if desired. We do not wish to be limited to the number of these screws used. 85 In place of pins or screws, the two rings may be soldered to each other either around the entire extent of the rings or at intervals.

It is entirely possible with our invention to have the wedding ring and the engagement 90 ring sold together so that the wedding ring will conform in design and in the conformation of the recess 14 exactly to the shape and structure of the engagement ring, though on the other hand it is entirely possible for the 100 jeweller to keep wedding rings cut out to fit certain forms of engagement rings and to afterwards fit the wedding ring to the engagement ring. Obviously the drawing is merely an illustration of the principle of our 105 invention and the invention may, of course, be embodied in a large number of different designs or forms.

It will be seen that our construction is particularly advantageous in that the engagement ring, which is for a longer or shorter period worn separate from the wed-

ding ring, is not modified in any way and that it is only the wedding ring which is modified and inasmuch as this ring is immediately worn with the engagement ring, 5 this cut-away portion or modification of it does not affect in any way its beauty as would be the case if the engagement ring were cut away or changed from its normal or conventional form.

10 We claim:—

A ring comprising an annular band of substantially the same cross sectional area throughout and having a flat side face, the

band being provided at one point with a crown setting laterally projecting beyond the 15 side faces of the ring, in combination with a wedding ring formed to provide a band of the same cross sectional area throughout having a flat side face adapted to fit against the flat side face of the first named ring and 20 cut away at one point to receive the laterally projecting portion of the crown setting.

In testimony whereof we hereunto affix our signatures.

HENRY M. DAYTON.
NELLIE DAYTON.
